UNITED STATES PATENT OFFICE.

EZRA W. VANDUZEN, OF NEWPORT, KENTUCKY.

FURNACE.

SPECIFICATION forming part of Letters Patent No. 360,182, dated March 29, 1887.

Application filed September 7, 1886. Serial No. 212,930. (No model.)

To all whom it may concern:

Be it known that I, EZRA W. VANDUZEN, a citizen of the United States, and a resident of Newport, in the county of Campbell and State 5 of Kentucky, have invented certain new and useful Improvements in Furnaces, of which the following is a specification.

My invention relates to furnaces more especially adapted to steam-boilers. It may be 10 applied to other purposes.

The first object of my invention is to provide a suitable lining for the doors and walls of a furnace, which accomplishes two purposes—first, to prevent the parts from burning 15 out and to resist the tendency of the heat to warp them out of shape; second, to allow a proper admission of air through orifices pierced in the doors and walls, delivering it to the furnace-chamber in a partially-heated condition, 20 increasing the efficiency in the combustion of the fuel.

Another object of my invention is to provide suitable means for admitting a graduated or regulated amount of air into the rear of 25 the fire-chamber through the ash-pit. In the ordinary furnace the combustion of the fire is more rapid and the heat the greatest at the rear, and in order to equalize the heat, causing the fuel to burn more rapidly in front and 30 more slowly in the rear, I have provided means for regulating the admission of air to the rear part of the ash-pit, and also means for retarding the admission of air through the grate-bars.

The several devices accomplishing these 35 objects are illustrated in the accompanying drawings, making a part of this specification, in which—

Figure 1 is a longitudinal vertical section of my improvement. Fig. 2 is a top plan view 40 on line x x , Fig. 1. Fig. 3 is a central vertical section of the door and lining. Fig. 4 is an inside perspective view of the door and lining. Fig. 5 is an elevation of the outside of the furnace-door. Fig. 6 is a front elevation of the 45 rear ash-pit doors, and Fig. 7 is a broken perspective of the rear grate-bars.

A represents the walls of the furnace; B, the boiler; C, the ash-pit; D, the division-wall in the ash-pit; E, the fire-chamber; F, the front 50 series of grate-bars, and G the rear series. The grate-bars G are supported at the rear end by the rear wall, H, which is provided with usual

arches for flues. The front ends of grate-bars G rest on the division-wall D. The rear ends of these grate-bars are bent or inclined upward, so as to keep an open space at the rear for the admission of air between and through the grate-bars. 55

F represents the front grate-bars, which are supported by the front wall and the partition-wall D. 60

α represents lugs on the grate-bars, to prevent their warping laterally out of line.

1 represents doors placed in orifices in the division-wall D, which divides the ash-pit in 65 two chambers. These doors are hinged to said division-wall to swing into and out of the orifices therein and are provided with orifices 2, for the admission of air into the rear ash-chamber, 3. These orifices may be covered 70 with a damper, if desired; but I prefer to regulate the quantity of air admitted by partially opening the doors.

As a further means of regulating the admission of air into the rear end of the combustion-chamber in a heated condition, the rear bars, G, are made to come together at the top surface and are pierced with orifices 4, to allow the escape of ashes and admission of air; but the rear grate-bars may be of the usual form 75 and still accomplish several of the objects of my invention.

g represents ribs, of which one or more may be used to prevent the bars or plates from warping. Two results are accomplished by 85 these rear bars—first, the small amount of air-openings retards a rapid combustion at the rear, and, second, maintains a nearly uniform heat and combustion of the fuel at the front and rear of the fire-chamber. 90

5 represents the lining of the furnace doors and walls. It is of shell form and rigidly attached thereto by bolts 10, forming an open space, into which the air is received, if desired, through orifices 9, pierced in the doors or 95 wall. It is shown at 6 as attached to both the doors and front wall of the furnace. This lining may be made of cast metal or fire-clay. It is provided with slots 7 and 8, which serve the following purposes: The slots 8 allow of 100 the lateral contraction and expansion of the face of the lining with little liability of warping or breaking, due to the heating of the same. The slots 7 are for the same purpose with ref-

erence to the contraction and expansion of the edges of the lining-shell.

I claim—

1. The combination, with a furnace having an ash-pit, of the division-wall D, separating the ash-pit into two chambers and supporting two sets of grate-bars, one having large air-spaces between the bars and the other small air-openings, said wall being provided with an orifice, and the door 1, located in said orifice and having orifices 2, substantially as described.

2. The combination, with a furnace having an ash-pit, of the division-wall D, separating the ash-pit into two chambers and provided with an orifice, two sets of grate-bars supported by the division-wall, the front set of grate-bars being open and the rear grate-bars abutting each other at their top surface and pierced with air-openings, and the perforated door 1, seated in the orifice and hinged to the division-wall to swing into and out of said orifice, substantially as described.

3. The combination, with the furnace having the rear wall, H, and ash-pit, and a division-wall, D, separating the ash-pit into two chambers, of a perforated door, 1, in the division-wall, the front grate-bars, F, and the rear grate-bars, G, supported by the division-wall and rear furnace-wall and provided with a series of perforations, 4, substantially as described.

4. The combination of the furnace ash-pit divided by the partition-wall D and the front furnace-wall, A, and rear wall, H, with the rear grate-bars, G, abutting each other at their top surface and pierced with the air-openings 35 4, said grate-bars supported at their ends, respectively, by the rear furnace-wall and the division-wall, and the open front grate-bars, F, supported at their ends, respectively, by the front furnace-wall and the division-wall, substantially as described.

5. A shell-lining, 5, attached to the door or wall of a furnace provided with slots pierced in its face, arranged as shown, substantially as specified.

6. A shell-lining, 5, provided with slots 7 and 8, pierced through said shell, attached to the door or wall of a furnace provided with slots pierced in its face, substantially as specified.

7. In combination with a shell-lining, 5, attached to door-plate 1, the air-openings 9 and slots 8, pierced through the door and lining, as specified.

In testimony whereof I have hereunto set my hand.

EZRA W. VANDUZEN.
